UNITED STATES PATENT OFFICE.

BERNARD M. ELY, OF OAKLEY, CINCINNATI, OHIO, ASSIGNOR, BY MESNE ASSIGNMENTS, TO INTERNATIONAL BUSINESS MACHINES CORPORATION, A CORPORATION OF NEW YORK.

GRINDING MILL.

Application filed February 13, 1917, Serial No. 148,330. Renewed March 18, 1924.

To all whom it may concern:

Be it known that I, BERNARD M. ELY, a citizen of the United States, residing at Oakley, Cincinnati, in the county of Hamilton and State of Ohio, have invented certain new and useful Improvements in Grinding Mills, of which the following is a specification.

This invention relates to improvements in mills for grinding grain, and especially to those for grinding coffee berries. In mechanism hitherto proposed for grinding grain, including coffee grinders, a plurality of sets of crushing elements, for breaking and grinding the grain respectively, have been provided, and these sets of elements have had connection with each other, so that the grain to be crushed is fed first to one of said sets of elements, where it is broken or coarsely ground and then passes to the other set of elements where it is more finely ground. In these mechanisms it also has been proposed to remove the chaff, dust and dirt from the grain intermediate the two crushing operations, by subjecting the grain to the action of an air current of such strength that it will carry off the chaff and lighter particles and allow the heavier particles to pass to the second set of crushing elements.

One of the important objects of this invention is to improve mechanism of the kind hereinbefore stated by so combining and correlating the parts as to have important advantages not inherent in the prior devices while preserving any valuable feature which is present therein.

Another important object of the invention is to provide an improved correlation of parts whereby a current of air of less strength than otherwise would be required will be adequate to effect a withdrawal of the impurities from the grain.

Another important purpose of the invention is to provide a grinding mechanism wherein the grain may be subjected to the action of a set of crushing elements and conveyed thence to and be acted upon by a second set of crushing elements, or may be acted upon by the second set only, at will. This object is secured by providing separate feeders, so correlated with the sets of crushing elements respectively that the grain supplied from one feeder will be subjected to the action of both sets of crushing elements,

while the grain supplied from the other feeder will be subjected to the action of the second set of crushing elements only.

A fourth important purpose of the invention is to provide a mill in which at the will of the operator the grain may (1) be preliminarily coarsely crushed or broken by a set of crushers or breakers, the impurities separated therefrom and the cleaned or purified grain more finely crushed by a second set of crushers, or (2) may be ground only. This object is secured by providing a first and a second set of crushers producing different degrees of fineness of grind, a conveyer for transferring the grain from one to the other, a separating means operable upon the grain in its passage from the first set to the second, and separate feeders of unground grain respectively connected with the sets of crushers.

A further important purpose of the invention is to provide a grinding mill having a conveyer and crushing elements, with means whereby the ill effects accruing from the conveying of the grain to the crushing elements at a faster rate than the crushing elements will accommodate are automatically overcome. This purpose is secured by providing a chamber so correlated with the conveyer and crushing elements fed by the latter that it will accommodate grain fed in excess of the capacity of the crushing element and will automatically return the grain when the crushing elements are capable of taking care of the same.

Another important purpose of the invention is to provide a mill having means of most practical, simple and beneficial nature for attaining all of the aforesaid objects.

In the accompanying drawings, I have illustrated the preferred embodiment of the invention when applied to the cleaning and grinding of coffee, but I would have it understood that this embodiment is merely exemplary and that changes in the details may be made without departing from the spirit of the invention or the scope of the subjoined claims. In said drawings, wherein like characters of reference are used to designate corresponding parts in the several views:

Fig. 1 is a longitudinal vertical section taken centrally through a coffee mill embodying the improvements, with certain parts in elevation;

Fig. 2 is a vertical transverse section on

line 2—2 of Fig. 1, looking in the direction of arrow *a*;

Fig. 3 is a vertical transverse section line 3—3, looking in the direction of the arrow *b*.

5 Fig. 4 is a detail perspective view of the head of the suction conduit, showing the lateral enlargement thereof and the prolonged opening therein.

The frame or casing of the present mill 10 is suitably formed to provide the first crusher chamber A, a second crusher chamber B, a conduit C leading from the first crusher chamber, a passageway D leading from the conduit to the second crusher chamber, a 15 chamber E opposite the second crusher chamber B, and a space F below the passageway D and between the chamber B and E. The passageway D is in open communication at one end with the conduit C and 20 at the other end with the chamber B, the latter communication being preferably provided through a downwardly extending spout 20 from the passageway entering a funnel-shaped inlet 21 at the upper end of 25 the chamber B.

In the space F there is mounted a motor, 30 whose casing indicated at G, has a base G' which in practice preferably constitutes the base of the mill casing. This motor is preferably of an electrical nature. It is directly connected to a shaft H, one end of which is directly connected to and drives a fan I, and the other end of which is directly connected to and drives the runner burr 22 forming one 35 of the crushing elements in the chamber B.

In this particular exemplification of the invention, the crushing elements in the chamber A are of a nature such as to break the grain—that is to say, they are, in the present 40 exemplification and preferably, composed of a rotative breaker drum 25, which cooperates with a suitable companion element 26 which is located at one side of the axis of the drum and is preferably roughened. It will 45 be noted that this element substantially forms one wall of the chamber and is eccentric to the axis of the drum. The crushing elements in the chamber B may be of any suitable construction. They are here 50 shown as being of a grinding nature, comprising the hereinbefore mentioned runner burr 22 and a stationary burr 23 having serrated or roughened confronting faces. These 55 grinders in practice should include appropriate means whereby the motion of the runner burr is automatically stopped when a hard foreign substance gets between the burrs. A desirable construction of grinding 60 mechanism for the chamber B is shown and described in my copending application, filed July 14, 1915, Serial No. 39,820, to which reference may be had for a further understanding relative thereto.

J designates a movable conveyer for trans- 5 mitting grain which has been partially

treated in the first crusher chamber A to the second crusher chamber B. This conveyer is preferably of the worm type, as here shown. The shaft H is connected by any suitable means,—as a train of gears 27, 70 28 and 29, for example—with the shafts 30 and 31 of the conveyer J and breaker drum 25, respectively.

K designates a feeding chamber which is 75 suitably connected to the crusher chamber A and supplies the grain to the latter. This feeder may be of any suitable nature, but preferably is formed with converging sides 32 and 33 extending from the top to the bottom thereof and opening at the lower 80 reduced end of the feeder into the chamber A, at a place which is eccentric to the axis of the drum 25.

L designates an air conduit which extends 85 from the fan chamber E to the conduit C. This conduit C has an opening 34 in one of its walls, through which it has communication with the conduit L, and the conduit L preferably has adjacent the said opening a laterally expanded head 35 with an opening 36 throughout its length, the opening 34 in the conduit C in such case being long, as shown best in Fig. 3. In other words, it is preferred to form the opening 34 substantially entirely across one wall of the conduit C and to provide the conduit L with a laterally expanded end having an opening co-extensive in length with the opening 34. A downwardly inclined spout 37 is 90 preferably provided within the conduit C. This spout extends from the opening 34 and forms a baffle in the path of the crushed grain, falling from the chamber. The grain falls thence upon another baffle 38. The latter is disposed between the end of 95 the spout and an air opening 39 formed in a wall of the conduit. The baffle 38 is arranged to discharge upon another baffle, 40, which extends to the chamber D and is inclined in a direction opposite to that of the baffle 38. An additional air opening, 41, is 100 preferably provided in the wall of the conduit C below the spout 37 and in the space separating the baffles 38 and 40. The air openings 39 and 41 are preferably independently regulated by valves 42 and 43 of 105 suitable kind.

Thus it will be seen that when the fan I is in motion it will create a current of air 110 which will pass from the opening 39 around the discharge end of the baffle 38 and thence upward and into the spout 37 and to the opening 34, through which opening it will flow to the fan casing E, through the conduit L. This current of air carries with it 115 the chaff, dust and dirt—that is, the impurities—which have been freed from the grain by the set of breaking elements 25 and 26, and the air, together with the impurities therein, is discharged into the fan 120 125 130

chamber E, and finally from the latter through an outlet 44' preferably into a suitable container, not shown. It will be understood that the partially treated grain is 5 spread out in its travel along the baffle 38 and is discharged from the latter in a thin sheet, and it will be noted that the correlation of the openings 39 and 41 with the space between the discharge end of the baffle 38 10 and the baffle 40 is such that the air passes through this thin sheet of falling grain in a direction which is at an angle to the direction of movement of the grain instead of in a direction which is parallel to the 15 movement of the grain. The baffles thus direct the air currents in particular defined paths through the falling grains, so that the separation of the impurities from the grain is effectively accomplished by a current of 20 air of less strength than otherwise would be required, and there is less danger of the current of air carrying off grain as well as impurities: and, moreover, the impact to which the grain is subjected in falling from 25 one baffle to another loosens any chaff etc. which may be adhering to the larger particles of the grain, whereby the withdrawal of the chaff etc. is facilitated. Again, it will be noted that the provision of two separate 30 and independently regulatable air inlet openings affords provision for the subjecting of the broken grain to the action of either one or both of two separate currents of air of independently regulatable strengths 35 at different places in the travel of the grain. When the inlets are arranged in the particular relation to the baffles and outlet spout shown in the accompanying drawings, the grain in its travel upon the baffle 38 and 40 between the upper wall of the spout and said baffle, is subjected to a current of air which removes the impurities which are upon the surface thereof and in its travel between the baffle 38 and the baffle 40 is subjected to 45 another current of air which removes the remaining impurities.

Obviously, the grain which has been thus broken and separated from its impurities is delivered to the conveyer J, and is conducted 50 by said conveyer and discharged into the second chamber B, wherein it is subjected to the action of the second set of crushing elements—namely, the runner burr 22 and the stationary burr 23. These burrs are relatively adjustable to grind to various degrees of fineness, as usual. The purified and ground grain is discharged from the chamber B, in the herein exemplified form of the invention, through an outlet 45' and into a 55 suitable container, not shown.

An important part of the present invention consists as already implied, in the provision of means whereby the grain may be ground in the chamber B without being 60 preliminarily crushed in the chamber A or

purified in the conduit C. To this end, the passageway D has communication with a second feeder chamber, marked M. This second feeder chamber opens at its lower end into the portion of the passageway D 70 situated after that portion of the passageway which opens into the conduit C. Hence, it will be noted that grain may be supplied through the feeder chamber M and will reach the crusher chamber B without first 75 passing through the chamber A or the conduit C. Another of the important features hereinbefore referred to has reference particularly to the prevention of the ill effects which would occur from the feeding of 80 grain to the chamber B faster than the set of crushing elements in the latter is capable of grinding the same, or at a time or in quantity which would result in the clogging of the action of the second set of crushing elements. It will be noted that in the form of the invention herein illustrated, the feeder chamber M is disposed immediately 85 above and is in open communication with one end of the passageway D. Hence, this 90 chamber M not only serves as a feeder for grain, which is not to be subjected to the action of the first set of crushing elements and to the purifying action of the air current, but also serves, when the grain is being fed from the feeder K, and hence is being subjected to action of the first set of crushing elements and to the purifying action 95 of the air currents, as an upper enlargement of the discharge end of the passageway 100 D into which any grain fed in excess of the capacity of the crushing elements in the chamber B is automatically forced and flows gravitally back into said passageway to be 105 delivered thence to the chamber B, when the quantity fed is below the capacity of the crushing elements in the latter. In other words, it serves at times as a feeder for grain which is not to be subjected to the action of 110 the first set of crushing elements or purified and at other times it serves to receive from the passageway D an excess of grain and thereby overcomes the ill effects which would follow congestion or clogging of grain in the discharge end of the latter, or in the chamber B.

It is apparent that when the grinding elements in the chamber B are relatively adjusted to pulverize the grain they will not take care of the grain as rapidly as when they merely granulate the same and hence in a machine intended to either granulate or to pulverize at will, it is desirable to regulate the feed of the grain to the breaker elements in the chamber A to thereby overcome 120 any possibility of the broken grain overflowing the chamber M. To this end, a valve of any suitable nature which will regulate the supply of grain to the chamber A is employed. One such valve—the same being 125 130

slidably mounted at the outlet from the feeder chamber K—is shown at 45 in Fig. 3. This valve has an opening 44 and by its adjustment variably regulates the extent of the communication of the feeder chamber K with the chamber A, as is apparent. The inlet 21 to the chamber B similarly is provided with a suitable valve, as the one shown at 46, which is adjustable to close said inlet 10 completely, or to open it either fully or partially as required. The valve 46 which I prefer is a slidably mounted plate having an opening 46'.

The operation and advantages of the 15 structure will be apparent from the foregoing description, and it will be understood that the form herein illustrated is merely exemplary and that changes may be made in the number or character of sets of crushing 20 elements and in other details without departing from the spirit of the invention or the scope of the subjoined claims. While I have herein referred to a first set of crushing 25 elements and a second set of crushing elements, each having a feeding chamber separate from the other, it of course will be understood that it is quite within the spirit of the invention to provide any suitable number of steps in such crushing elements 30 and to provide all or certain of the same only, with their separate feeding chambers. Hence, the terms, first crusher chamber or set of first crushing elements, or second crusher chamber or set of second crushing 35 elements are intended to be construed broadly, being merely employed as a convenient way to distinguish one of said chambers and its crushing devices from another.

I have before referred to the ill effects 40 which occur from the feeding of grain to the chamber B faster than the set of crushing elements of the latter is capable of grinding the same or at a time or in quantity which would result in the clogging of 45 the action of the second set of crushing elements. It will be understood that there may be several causes in the operation of the mill which render it advisable to temporarily discharge a part or all of the grain 50 into the overflow chamber formed by the feeder M, and among these there may be mentioned a failure of the grinding elements in the chamber B to operate for a short period or a choking of said grinding elements 55 due to foreign substances. In any of these events, the coffee passing to the grinding elements would be forced upward into the feeder M. These causes, and any other cause which makes it advisable temporarily 60 to supply grain to the overflow chamber are all intended to be included in the expression to the effect that said chamber receives grain which is fed faster than the capacity of the grinding elements.

65 Having thus described the invention what

I believe to be new and desire to secure by Letters Patent, and what I therefore claim, is:—

1. A grinding mill having consecutively operable primary and secondary crushing 70 means provided with independent direct feeders, suction cleaning means to which the product of the primary crushing means is subjected, and means for removing the cleaned product from the influence of the 75 cleaning means and conducting it to the feeder of the secondary crushing means.

2. A grinding mill having consecutively operable primary and secondary crushing 80 means, an independent gravitally acting feeder in direct communication with each of said crushing means, means for conveying the product of the primary crushing means to the feeder of the secondary crushing means, and means for suctionally cleaning 85 the product in transit between the primary crushing means and said conveying means.

3. In a grain grinding mill, the combination of a breaking means, and a grinding means, each of a nature to initially act upon the berries or like grain in loose condition and one being of a nature to act successively to the other, means subjecting the broken grain intermediate the breaking means and grinding means to a current of air for the 90 removal of the impurities therefrom, means for conveying the broken and purified grain from the breaking means to the grinding means, means through which grain to be broken, purified and ground is fed to the 95 breaking means, and a separate means through which grain may be fed to the grinding means without passing through the breaking means and outside the sphere of influence of the current of air. 100

4. In a grinding mill, a first crusher chamber, crushing means including a rotative breaker therein, a conduit leading from the crusher chamber, a second crusher chamber, crushing devices including a runner burr 110 therein, a passageway through which the conduit has communication with the second crusher chamber, a rotative conveyer in the passageway, a shaft arranged substantially parallel with the conveyer and having one of its ends extending into the second crusher chamber and carrying the runner burr, a chamber at the opposite end of the shaft, a fan mounted on said shaft in said chamber, a conduit connecting the fan chamber with 115 the first-mentioned chamber, means for driving the shaft and gearing connecting the shaft with the conveyer and the breaker.

5. A grinding mill having primary and secondary crushing means adapted, selectively, for initial and consecutive action upon the grain and accessible respectively through independent feed chambers, and a conveyor for conducting the product of the primary crushing means, unaffected by grav- 125 130

- ity, to the feed chamber of the secondary crushing means from which it is fed to said secondary crushing means.
6. A grinding mill having primary and secondary crushing means, adapted, selectively, for initial and consecutive action upon the grain, an independently acting feeder disposed in operative relation with the secondary crushing means and a force feed conveyor for conducting the product of the primary crushing means to the secondary crushing means and to the feeder therefor in which excess crushed material may be temporarily stored.
- 15 7. A grinding mill having primary and secondary crushing means adapted, selectively, for initial and consecutive action upon the grain, a gravitally-acting feeder disposed in juxtaposition to the secondary crushing means for feeding material directly to said secondary crushing means, and a force feed conveyor for conducting the product of the primary crushing means into the path of communication between said feeder and the secondary crushing means.
- 20 8. A grinding mill having primary and secondary crushing means adapted, selectively, for initial and consecutive action upon the grain, a gravitally acting feeder disposed in operative relation with the secondary crushing means for directly feeding material thereto or to constitute an expansion or over-flow chamber therefor, and a force feed conveyor for conducting the product of the primary crushing means to secondary crushing means and to the expansion or over-flow chamber.
- 25 9. In a grinding mill, the combination of breaking means, a grinding means, a conveyor for conducting the broken grain from the breaking means to the grinding means, and means forming a chamber which is open to the conveyer and receives therefrom grain fed in excess of the capacity of the grinding means, to thereby avoid choking of the latter, said chamber being disposed above the conveyer so as to return the grain thereto gravitally when the quantity being fed thereby is less than the capacity of the grinding means.
- 30 10. In a grinding mill, the combination of a first and a second crushing means, each of a nature to act initially upon berries or like grain in loose condition and one being of a nature to act successively to the other, means for conveying the grain from one to the other, a feeder connected to the first crushing means, and a separate feeder for the second crushing means, the latter feeder being correlated with the conveyer and second crushing means to act as an overflow chamber connected with the conveyer and to supply grains to the second crushing means which are not to be subjected to the action of the first crushing means.
- 35 11. In a grinding mill, the combination of a first and a second crushing means, means for conveying the grain from one to the other, including a passageway and a conveyer in the passageway, a feeder for the first crushing means, and a separate feeder for the second crushing means, the latter feeder being mounted above and in open communication with the discharge end of the passageway to act as an overflow chamber to receive from the latter grains fed in excess of the capacity of the second crushing means and to return said grain gravitally when the supply is below the capacity of said crushing means, and also to supply to the second crushing means grains which are not to be subjected to the action of the first crushing means.
- 40 12. In a grinding mill, the combination of a first and a second crushing means, each of a nature to act initially upon berries or like grain in loose condition and one being of a nature to act successively to the other, a conduit connected with the first crushing means, a passageway leading from the conduit to the second crushing means, a conveyer in the passageway, a feeder connected to the first crushing means, means for creating a current of air in the conduit to separate the impurities from the grains therein, and a separate feeder mounted above and in open communication with the discharge end of the passageway and open at the top to permit the feeding of material directly thereto, for the purposes specified.
- 45 13. In a grinding mill, the combination of means forming a breaker chamber, a conduit leading therefrom, a feeder chamber connected to the breaker chamber, means connected to the conduit for creating a current of air therethrough, means forming a grinder chamber, breaking and grinding means in the breaker and grinder chambers respectively, means forming a passageway extending from the discharge end of the conduit to the inlet of the grinder chamber, a rotative conveyer in the passageway, and means forming a feeder chamber which is open to passageway and is disposed opposite to the grinder chamber, the latter feeder chamber being arranged to receive broken and purified grains fed by the conveyer in excess of the capacity of the grinding means and to return the same to the conveyer when the quantity being fed is less than the capacity of the grinding means, and also to supply to the grinder chamber grains which are to be ground without being broken and purified.
- 50 14. A grinding mill having a crushing means and a conduit through which the grain moves by gravity and which is provided with baffles for causing the grain to follow a zig-zag course, and means for producing currents of air through the conduit,
- 55 60 65 70 75 80 85 90 95 100 105 110 115 120 125 130

one of said currents moving counter to the column of grain and another intersecting the first named current.

15. A grinding mill having a crushing means and a conduit through which the grain moves by gravity and which is provided with baffles for causing the grain to follow a zig-zag course, and means for causing currents of air to traverse the conduit respectively in counter and intersecting relation with the path of the grain therethrough.

16. A grinding mill having a crushing means and a conduit provided with air inlet and outlet openings, means for inducing a current of air through the conduit between said openings, and a grain directing baffle arranged in baffling relation with the current of air between said openings, the conduit having a further inlet for directing a current of air in intersecting relation with the baffled current.

17. A grinding mill having a crushing means and a conduit provided with air inlet and outlet openings, means for inducing a current of air through the conduit between said openings, and a grain directing baffle arranged in baffling relation with the current of air between the openings, the conduit having a further inlet for directing a second current of air in convergent relation with a portion of the baffled grain.

18. A grinding mill having crushing means and a conduit provided with air inlet and outlet openings, means for inducing convergent currents of air through the conduit toward said outlet opening, and a grain directing baffle arranged in baffling relation with one of said currents of air.

40 19. A grinding mill having crushing means and a conduit provided with an air outlet and a plurality of air inlets, means for inducing convergent currents of air through the conduit from said inlets toward the outlet, a grain directing baffle arranged in baffling relation with one of said currents of air, and means for proportionately varying the capacities of the inlet openings.

50 20. A grinding mill having crushing means and a conduit provided with an air outlet and a plurality of air inlets, means for inducing convergent currents of air through the conduit from said inlets toward the outlet, a grain directing baffle arranged in baffling relation with one of said currents of air, and independent means for relatively varying the capacities of said air inlet openings.

60 21. In a grinding mill, the combination of crushing means, a conduit leading therefrom, a baffle in the path of grain traversing the conduit, said conduit having an air outlet opening above the plane of the lower edge of the baffle and an air inlet opening rearward of the plane of said lower edge of

the baffle, and means for creating a current of air from the inlet opening to the outlet opening.

22. In a grinding mill, crushing means, a conduit leading therefrom, a spout extending inclinatorily partway across the conduit, the upper surface of the spout forming a baffle in the path of grain traversing the conduit, said conduit having an air outlet opening which registers with the opening through the spout and also having an air inlet opening rearward of the plane of the lower end of the spout, and means for creating a current of air within the conduit, from the inlet opening and through the spout and outlet opening.

23. In a grinding mill the combination of crushing means, a conduit leading therefrom and having an air outlet opening, a spout communicating with said opening and extending inclinatorily partway across the conduit and into the path of grain traversing the conduit, means for creating a current of air in the conduit and spout, and a baffle in the conduit, the end of said spout being directed toward and lying in juxtaposition to the face of said baffle and said conduit having an air inlet opening so arranged that air moving from the air inlet opening to the air outlet opening is caused to flow across the body of grain falling from the discharge end of said baffle and into said spout along the face of the body of falling grain.

24. In a grinding mill, crushing means, a conduit leading therefrom, a spout extending inclinatorily partway across the conduit, the upper surface of the spout forming a baffle in the path of grain traversing the conduit and the conduit having an outlet opening which registers with the opening through the spout, a baffle below the spout and spaced from the lower end thereof, the conduit also having an air inlet opening, and means for creating a current of air within the conduit, from the inlet opening and through the spout and outlet opening.

25. In a grinding mill, crushing means, a conduit leading therefrom, a spout extending inclinatorily partway across the conduit, the upper surface of the spout forming a baffle in the path of grain traversing the conduit and the conduit having an outlet opening which registers with the opening through the spout, a baffle below the spout arranged in zig zag relation therewith, and spaced from the lower end thereof, the conduit also having an air inlet opening arranged rearward of the vertical plane of the lower end of the spout and presented toward the upper face of the lower baffle, and means for creating a current of air within the conduit, from the inlet opening and through the spout and outlet opening.

26. In a grinding mill, crushing means, a conduit leading therefrom, a spout extend-

- ing inclinatorily partway across the conduit, the upper surface of the spout forming a baffle in the path of the grain traversing the conduit and the conduit having an outlet opening which registers with the opening through the spout, a second baffle disposed in zig zag relation with the spout and receiving the grain therefrom, said conduit having a plurality of air inlet openings 5 respectively arranged on opposite sides of the second baffle, and means for creating a current of air from the inlet openings, within the conduit and through the spout and outlet openings.
- 15 27. In a grinding mill, crushing means, a conduit leading therefrom, a spout extending inclinatorily partway across the conduit, the upper surface of the spout forming a baffle in the path of the grain traversing the conduit and the conduit having an outlet opening which registers with the opening through the spout, a second baffle disposed in zig zag relation with the spout and receiving the grain therefrom, a third baffle, 20 inclined oppositely to the second baffle and receiving the grain therefrom, the conduit also having a plurality of air inlet openings, one of which is arranged rearward of the space between the second and third baffles and the other in advance of said space, and means for creating a current of air from the inlet openings, within the conduit and through the spout and outlet openings.
- 25 28. In a grinding mill, the combination of crushing means, a conduit leading therefrom, a baffle in the path of grain traversing the conduit, said conduit having an air outlet opening located above the plane of the lower edge of the baffle, an air inlet 30 opening located rearward of the vertical plane intersecting the lower edge of the baffle, an air inlet opening between the lower end of the baffle and the air outlet opening, and means for creating a current of air from the inlet openings to the outlet opening.
- 35 29. In a grinding mill, the combination of crushing means, a conduit leading therefrom, a baffle in the path of grain traversing the conduit, said conduit having an air outlet opening located above the plane of the lower edge of the baffle, an air inlet opening located rearward of the vertical plane intersecting the lower edge of the baffle, an air 40 inlet opening between the lower end of the baffle and the air outlet opening, means for independently controlling the inlet openings, and means for creating a current of air between either inlet opening and the outlet opening.
- 45 30. In a grinding mill, the combination of crushing means, a conduit leading therefrom, an outlet air opening therein, a plurality of baffles arranged in a zig-zag relation in said conduit, one of said baffles dis- 50 charging against the succeeding baffle and forming a space therebetween, the conduit having air inlet openings on opposite sides of the space between the baffles and below the outlet opening and means for creating a current of air from the inlet openings to the outlet opening.
- 55 31. In a grinding mill, the combination of means forming a plurality of chambers, and means for conducting the grain from one chamber to the other and purifying it in its passage between the chambers, including a conduit, a series of baffles arranged in a zig zag relation in the path of the grain traversing the conduit and discharging the grain from one to the other, the conduit having an air outlet opening adjacent the undersurface of the uppermost baffle and also having a plurality of air inlet openings below the outlet opening and on opposite sides of the intermediate baffle of the series, and means for creating a current of air from the inlet openings to the outlet opening.
- 60 32. In a grinding mill, the combination of means forming a plurality of chambers, and means for conducting the grain from one chamber to the other and purifying it in its passage between the chambers, including a conduit, a series of baffles arranged in a zig zag relation in the path of the grain traversing the conduit and discharging the grain from one to the other, the conduit having an air outlet opening adjacent the undersurface of the uppermost baffles and also having a plurality of air inlet openings below the outlet opening and on opposite sides of the intermediate baffle of the series, means for independently regulating the air inlet openings and means for creating a current of air from the inlet openings to the outlet opening.
- 65 33. In a grinding mill, the combination of means forming a plurality of chambers, and means for conducting the grain from one chamber to the other and purifying it in its passage between the chambers, including a conduit, having an air outlet opening and an air inlet opening, a spout extending from the outlet opening inclinatorily partway across the conduit, in the path of the grain traversing the conduit, the upper surface of the conduit forming a baffle for the grain and the lower surface thereof forming a baffle in the path of the air flowing from the inlet to the outlet, a second baffle, inclined oppositely to the spout and receiving the grain therefrom, a third baffle inclined oppositely to the second baffle and receiving the grain therefrom, the conduit also having an air inlet so disposed that air flows through the space between the second and third conduit, and means for creating a current of air from the air inlets, within the conduit and through the spout and outlet.
- 70 34. In a grinding mill, a plurality of 75

crushing means, and means for conducting the grain from one to the other and purifying it in its passage, comprising a conduit extending from the first crushing means, a 5 conveyer between the conduit and the second crushing means, a plurality of baffles arranged in a zig zag relation within the conduit, in the path of the grain traveling from the first crushing means to the conveyer, said conduit having an air inlet opening and an air outlet opening, and means connected to one of the openings for creating a current of air in the conduit.

35. In a grinding mill, a plurality of 15 crushing means, and means for conducting the grain from one to the other and purifying it in its passage, comprising a conduit extending from the first crushing means, a conveyer between the conduit and the second 20 crushing means, a series of baffles arranged in a zig zag relation within the conduit, in the path of the grain traveling from the first crushing means to the conveyer, said conduit having a plurality of independently regulatable air inlet openings respectively disposed on opposite sides of the intermediate baffle of the series of baffles, the conduit also having an air outlet opening, and means connected to one of the openings for creating a 25 current of air in the conduit.

36. In a grinding mill, crushing means, a conduit extending therefrom, an air conduit having a laterally enlarged head with a prolonged inlet opening therein presented toward the first mentioned conduit, the first named conduit having an outlet opening which is of substantially the same dimensions as the inlet opening in the head of the second conduit and registers therewith, and 40 means for creating a current of air within the conduits and through said openings and head.

37. In a grinding mill, crushing means, a conduit extending therefrom, a baffle interposed in the path of the grain traversing the conduit, means forming a spout in advance of the baffle, an air conduit having a laterally enlarged head with a prolonged opening therein, the first-mentioned conduit 45 having an air outlet opening whose dimensions are substantially co-extensive with the dimensions of the opening in the head of the second conduit, said openings registering with each other, and means for creating a current of air within the conduits, head and spout.

38. In a grinding mill, crushing means, a conduit extending therefrom and having an air inlet opening and an air outlet opening, 50 a spout extending from the air outlet opening inclinatorily partway across the conduit and in the path of the grain being dis-

charged from the crushing means, a baffle inclined oppositely to the spout and receiving the grain from an external surface of the latter, an air conduit, having a laterally enlarged head with a prolonged inlet opening which registers with the outlet opening in the first-mentioned conduit, the dimensions of the latter opening being substantially the same as the inlet opening to the head, and means for creating a current of air within the conduits and through the spout and head.

39. In a grain grinding mill, the combination of a crushing means and a grinding means of a nature to act successively upon berries or like grain in loose condition, means for conducting crushed grain from the crushing to the grinding means comprising a substantially vertical passageway, a horizontal passageway at the bottom thereof, a conveyor in said passageway, an outlet in the bottom of the passageway out of alignment with the vertical passageway and above the grinding means, and a feed hopper above the conveyor and in alignment with the outlet opening of such a capacity as to receive any excess material fed by the conveyor and which is in excess of the capacity of the grinding means.

40. A combined coffee refining and pulverizing machine, comprising means for cracking the coffee, means for pulverizing the cracked coffee, means for supplying the cracked coffee to the pulverizing means, means for removing chaff from the cracked coffee, and means having provisions adapted to permit the direct introduction of uncracked coffee to the pulverizing means whereby coffee may be directly pulverized without previous cracking and without removal of chaff-like material.

41. A combined coffee cracking and pulverizing machine comprising in combination, means for cracking the coffee, means for pulverizing the cracked coffee, means for conveying the cracked coffee to the pulverizing means, a supplemental storage chamber receiving excess cracked material delivered by the conveying means during the relatively slower pulverizing operations, said chamber being arranged to effect subsequent automatic delivery of the excess material stored therein to the pulverizing means when the latter has pulverized the material delivered directly thereto by the conveying means, and means disposed intermediate the cracking and pulverizing means for removing chaff from said cracked coffee prior to the pulverizing operation.

In testimony whereof I affix my signature.

BERNARD M. ELY.
